UNITED STATES PATENT OFFICE.

VINCENZO SQUEGLIA, OF NEW HAVEN, CONNECTICUT.

NIGHT-LIGHT.

1,259,921.

Specification of Letters Patent. Patented Mar. 19, 1918.

Application filed September 11, 1917. Serial No. 190,721.

To all whom it may concern:

Be it known that I, VINCENZO SQUEGLIA, a subject of the King of Italy, residing at New Haven, in the county of New Haven 5 and State of Connecticut, have invented a new and useful Improvement in Night-Lights; and I do hereby declare the following, when taken in connection with the accompanying drawings and the characters of 10 reference marked thereon, to be a full, clear, and exact description of the same, and which said drawings constitute part of this application, and represent, in—

Figure 1 a side view partly in section, of 15 a night light constructed in accordance with my invention.

Fig. 2 a top or plan view of the same with the candle removed.

This invention relates to an improvement 20 in night lights which commonly comprise a cup or holder and a candle to be set into the cup. A common form of these candles comprises a body of paraffin, wax or other suitable material formed with a centrally 25 arranged longitudinal passage through which the wick is passed, the lower end of the wick being connected to a disk of metal formed with prongs to be inserted into the lower end of the candle. To form these 30 metal disks and connect the wicks with them, involves time and expense, as well as material for the disks.

The object of this invention is to provide 35 a wick of sufficient length to be used with several candles, and a holder for the wick; and the invention consists in the construction hereinafter described and particularly recited in the claims.

In carrying out my invention I employ a 40 candle body 3 formed from paraffin, wax or other suitable material. This candle is adapted to be set into a cup or socket 4 such as usually employed for night lights. The candle body is formed with a central longitudinal passage 5 for the passage through 45 it of a wick 6. This wick is formed from a

long strip of cord or other suitable material which is preferably wound in a flat coil to rest in the bottom of the cup, one end of the wick passing upward through an eye 7 50 formed in one end of a wick-holder 8, this wick-holder having a flat portion 9 which rests upon the coil and holds it in place, and the outer end extends upward over the top of the cup and downward upon the outside 55 forming a clip to hold the wick-holder in place, and provides a handle by which the candle may be lifted out of the candle-holder when desired. The end of the wick is passed upward above the upper end of the 60 candle to provide for lighting in the usual way; and when the candle is consumed the end of the wick is drawn upward and another candle placed over it. Thus a single 65 piece of wicking may be used with several candles. With this construction I avoid the necessity of attaching the separate wicks to wick-holders and connecting those wick-holders with the individual candles.

I claim:—

1. A night light comprising a candle 70 formed with a longitudinal opening, combined with a wick longer than the length of the candle, the said wick coiled below the candle, and a wick-holder below the candle 75 and through which the wick extends.

2. A night light comprising a candle-holder, a candle formed with a longitudinal 80 passage and adapted to set into the holder, a wick coiled in the bottom of the holder and one end adapted to be passed upward through 85 the candle, and a wick-holder provided with an eye through which the wick extends, said holder extending upward over the top of the holder and down upon the outside thereof.

In testimony whereof, I have signed this specification in the presence of two subscribing witnesses.

VINCENZO SQUEGLIA.

Witnesses:

MAURO FADDETTO,
DOMENIK SCARASCO.
